(No Model.)

S. McLEAN.
DOOR SECURER.

No. 436,611.

Patented Sept. 16, 1890.

UNITED STATES PATENT OFFICE.

SETH MCLEAN, OF BAY CITY, MICHIGAN.

DOOR-SECURER.

SPECIFICATION forming part of Letters Patent No. 436,611, dated September 16, 1890.

Application filed October 18, 1889. Renewed July 28, 1890. Serial No. 360,135. (No model.)

To all whom it may concern:

Be it known that I, SETH MCLEAN, a citizen of the United States, residing at Bay City, in the county of Bay and State of Michigan, have 5 invented a certain new and useful Improvement in Bolts for Locking Doors; and I declare the following to be a full, clear, and exact description of the invention, such as will enable others to make and use it, reference being had to the accompanying drawings, and to the letters of reference marked thereon, which form a part of this specification.

My invention relates to improvements in devices for fastening or securing doors in a 15 closed position; and it consists in a suitable plate secured to the door-jamb and with a portion projecting beyond the door and provided with a vertical tapering groove of a dovetail form, and a securing bolt or device arranged 20 with a portion provided with flanges adapted to fit into the said dovetailed groove and having a portion projecting over the closed door.

The invention also consists in the combination and arrangement of the parts, as I shall 25 presently proceed to explain, and which will be specifically pointed out in the claims of this specification.

The object of this invention is to provide 30 devices whereby doors may be secured in a closed position in an effective manner, and which will operate on doors of varying thickness or on doors which have been imperfectly fitted and hung or which have changed in relation to the jamb by shrinkage, sagging, or 35 otherwise. I attain this object by means of the devices illustrated in the accompanying drawings, in which—

Figure 1 is a front view in elevation of a 40 portion of a door and casing with my improvement attached thereto in position for securing the door. Fig. 2 is the same with the parts disconnected to allow the door to be opened. Fig. 3 is a transverse section of Fig. 1, taken at the dotted line $\alpha\alpha$. Fig. 4 is a face view 45 in elevation of the device with the parts connected together.

The same letters of reference indicate like parts throughout the several views.

a represents a portion of the jamb-casing 50 of a door-frame.

c is the face-casing, and *d* is the door.

e is a plate secured by screws to the jamb *a*, with a portion *f* thereof projecting outwardly beyond the door. On the outer side and facing the door the portion *f* is provided 55 with a vertical tapering groove *g*, the wider portion of the groove being at the upper edge of the plate, and the inner lateral wall *h* of the groove is arranged vertically with the plate, while the outer lateral wall *i* is inclined 60 to form the taper of the groove, and the walls are also arranged to project into the groove or converge, so that the groove has the form of a dovetail.

j is a securing piece or bolt, provided with 65 the diverging sides *k* and *l*, having a longitudinal taper fitted to pass into the tapering dovetailed groove *g*, while *m* is a portion of the piece which projects over the door, the inner side *n* thereof, which bears against the 70 door, being slightly rounded transversely; and the piece is also provided with a stem or handle portion *o*, and a cord or chain *p* is secured to the stem and to the casing of the door-frame. When the door is in a closed position, 75 as shown in Figs. 1, 2, and 3, the piece *j* is passed into the groove *g*, which, having its outer wall *i* sloping inwardly, causes the side 80 *n* of the piece to bear firmly against the door, and the bevel of the inner wall *h*, reaching 85 over the beveled side *l* of the piece, prevents the piece from turning when the door is pushed outward for opening, so that the door is securely held in a closed position, while to release the door the piece *j* is removed, and the cord *p* then retains the piece suspended until again needed.

Of course it will be understood that while I have shown and described the groove *g* as being in the form of a dovetail and provided 90 with inwardly-beveled front and rear walls, the contour or shape of the walls may be other than a plane bevel and produce the same result, for so long as the outer edge of the rear wall *h* is arranged to overhang or project into 95 the groove the piece *j*, being fitted thereto, will be held from turning when in position in the groove and against the door.

It will be seen that while my improved device is simple and easily made and attached 100 to the doorway, it is also exceedingly strong and durable and will adjust itself to the door

under all ordinary circumstances, as the settling or sagging of the door or building does not change the position of the parts and any shrinkage or swelling of the door does not affect its operation, as the taper of the piece and groove allows the piece *j* to be pushed in place until the door has a firm bearing against the jamb, and then the piece is in a position to hold the door securely, as should the piece not entirely fill the groove *g* when the parts are brought to a firm bearing against the door the piece is allowed to tilt outwardly by the rounded side *n* until the beveled side *l* of the piece comes in contact with the inner wall *h*, and then the parts are in a position to retain the door in the same manner as if the piece were allowed to pass downward to entirely fill the groove.

Having described my invention, what I claim as new, and desire to secure by Letters Patent, is—

1. A device for securing doors, consisting of a metal plate provided on one side of one end portion with a transverse tapering groove having the outer edge of its inner side wall over-

hanging or projecting into the groove and a securing-bolt having one side tapering and provided with lateral edges fitted to pass into the said groove and engage with the lateral walls thereof, and provided with a longitudinal flange or rib projecting outwardly from the said lateral edges, substantially as described.

2. In a door-securer, the combination, with the door and casing, of the plate secured to the jamb-casing and with a portion projecting beyond the door and provided with a dovetailed groove having a vertical inner side wall and a sloping outer wall, and the securing-piece having one side tapering and provided with beveled edges fitted to pass into the said dovetailed groove and with a laterally-projecting flange reaching over the door, substantially as set forth.

Intestimony whereof I have hereunto affixed my name in the presence of two witnesses.

SETH MCLEAN.
